US0D1004069S

(12) **United States Design Patent** (10) Patent No.: **US D1,004,069 S**
(45) Date of Patent: ** Nov. 7, 2023

(54) **ODOR POD RECEPTACLE**

(71) Applicant: **simplehuman, LLC**, Torrance, CA (US)

(72) Inventors: **Frank Yang**, Rancho Palos Verdes, CA (US); **Tzu-Hao Wei**, Hacienda Heights, CA (US); **Shinwei Rhoda Yen**, Rolling Hills Estates, CA (US); **Myk Lum**, Irvine, CA (US); **Adam Wade**, Rancho Santa Margarita, CA (US)

(73) Assignee: **simplehuman, LLC**, Torrance, CA (US)

(**) Term: **15 Years**

(21) Appl. No.: **29/867,654**

(22) Filed: **Nov. 2, 2022**
